COOLING RACK FOR ADHESIVE BINDINGS

Henry N. Staats, Deerfield, Ill., assignor to General
Binding Corporation, Northbrook, Ill.

Filed Nov. 26, 1973, Ser. No. 419,129

Term of patent 14 years

Int. Cl. D19—02

U.S. Cl. D19—75

FIG. 1 is a perspective view of a cooling rack for adhesive bindings showing my new design;
FIG. 2 is a right side elevational view;
FIG. 3 is a rear elevational view; and
FIG. 4 is a bottom plan view.

I claim:

The ornamental design for a cooling rack for adhesive bindings, as shown and described.
